(57) **CLAIM**

The ornamental design for dispensing valve, as shown and described herein.

DESCRIPTION

FIG. 1 is a top, front and right side perspective view of the dispensing valve;

FIG. 2 is a top view thereof;

FIG. 3 is a rear view thereof;

FIG. 4 is a front view thereof;

FIG. 5 is a left side view thereof, which is a mirror image of the right side view; and,

FIG. 6 is a right side view thereof, which is a mirror image of the left side view.

In the drawings, the broken lines depict unclaimed environmental subject matter only and form no part of the claimed design.
